STEAMSHIP-DRIVING MECHANISM.

Application filed December 5, 1921. Serial No. 519,898.

The present invention relates to gearing for steamships and more specially to a construction for increasing the life of certain types of toothed gearing.

One of the important fields for toothed gearing is the utilization of such gears for speed reduction. One service where speed reduction is accomplished by highly developed types of toothed gearing is the steam-turbine propelled steamship. In this branch of gearing the very high speed of the turbine or turbines is reduced through the medium of large expensive gearing sets of the single reduction type and in many cases of the double reduction type to the relatively slow speed required by a screw propeller. This type of mechanism is necessarily very strong and very heavy because of the horsepower which is centralized in and transmitted to the propeller shaft. It is common practice to arrange a plurality of turbines to drive a single propeller shaft through the intermediary of such reduction gearing. In this type of construction it is usual to provide pairs of very large gears connected directly to a propeller shaft and pairs of relatively small pinions connected either directly to the shafts of the turbines in the single reduction type or in the double reduction type to a second set of gearing which may comprise another pair of relatively large gears and a corresponding pair of relatively small pinions, with the final and smallest pair of pinions connected directly to the turbine shafts. In both types of mechanism the train of gears is run a very large percentage of the time in one direction because the steamship moves forward nearly all of the time and goes astern only a small part of the time. In view of the substantially continuous duty imposed upon the forward side of the gear teeth it follows that the forward side of the gear teeth is worn out when the backing or stern side of the teeth is substantially unworn. The wear on the forward side is accentuated by sliding and grinding of the contacting gear teeth due to vibration of the ship while the teeth are transmitting the heavy load. This wear may also be accentuated by lack of efficient lubrication, accumulation of dirt and grit, and by many other causes which may shorten the life of the gears. The ratio between a pinion and its corresponding gear may be as great as twenty-five or more to one so

that such pinion may receive twenty-five times or more as much wear as the corresponding gear wheel. Therefore, the pinion wears out much quicker than its companion gear wheel. It is the practice in this art to provide helical teeth for this type of gearing in order to properly transmit the load and at the same time avoid excessive end thrust and vibration and other difficulties which are liable to attend straight teeth. The practice heretofore in the art has been to run the train of gears until the pinions are worn out and then lay up the ship until the gearing can be dismantled and new pinions substituted and also other worn out parts. This practice is expensive and it is also dangerous because often times pinions are run when they are liable to break down at sea. Furthermore, after the gear teeth have been worn to the extent that the faces of the teeth no longer are of correct contour, the wear increases very rapidly and the life of such teeth cannot be accurately predicted and they are liable to break unexpectedly.

The present invention solves the difficulties of the known art by greatly extending or prolonging the effective life of the gearing in such manner that much longer wear of a single set of gears can be obtained without replacement. One embodiment of the present invention comprises constructing the teeth of the large gears and also the teeth of the pinions so that any pinion and shaft or large gear may be removed from its bearings and turned end for end and replaced in its bearings and the teeth on the gears and pinions will continue to mesh properly without changing the desired direction of rotation of the train of gears and propeller shafting. When the pinion is reversed, the back faces of the teeth on the pinion become the forward driving faces and in view of the lack of wear on such back faces, the gear set is substantially new as far as the efficiency of the forward rotation is concerned. It will be noted that the change in the driving faces of the gears or pinions does not change the desired direction of rotation so that the direction of movement being transmitted through the gear set from the driving shaft to final driven shaft is the same as it was before the change is made.

The present invention also contemplates certain constructions in the system of reduction gearing whereby it is possible to re-

100

105

110

verse the faces of any of the gears of a train of gears, thereby still further increasing the life of the gear set.

After having described the present invention in general terms, it may be stated that the principal object of this invention is the apparatus for prolonging the life of gear sets and the like by means of congruous tooth shapes.

10 Another object of the present invention is the mechanical design of a reduction gear set for turbine ship propulsion and the transmitting of power through gearing wherein the gearing is so constructed that 15 the stern or reversed faces of the gear teeth may be arranged to comprise the driving faces of the gears by reversing certain elements in the gearing.

A still further and more specific object of 20 the present invention is that improvement in reduction gearing comprising pairs of gear members provided with helical gear teeth and with the angle of inclination of any portion of a tooth upon one gear having 25 a congruous counterpart in a corresponding tooth on a companion gear.

Other and further objects of the present invention will in part be obvious and will 30 in part be pointed out hereinafter in the specification following by reference to the accompanying drawings forming a part of this application and in which like parts are indicated by like characters throughout the several figures thereof.

35 Realizing that the present invention may be embodied in constructions other than those herein illustrated, and described it is desired that the disclosure herewith shall be considered as illustrative and not in the 40 limiting sense, and that the scope of the claims shall be as broad as the language thereof when interpreted on the disclosure will admit.

Fig. 1 is a plane view showing the intermediate and driven gears of a double reduction gear unit adapted for use with a steamship turbine;

Figure 2 is a diagrammatic plan view showing the pinions and intermediate gears 50 of the device shown in Figure 1;

Figure 3 is a diagrammatic detail illustrating the relation of parts;

Figure 4 is a view similar to Figure 3 showing one gear member reversed;

55 Figure 5 is a diagrammatic view of an elevation of Figure 3 looking in the direction of the arrow X and showing the stern faces of the gear teeth as shaded;

Figure 6 illustrates certain of the parts 60 in Figure 5 when reversed in position;

Figure 7 is a detail sectional view showing the construction of the large gear shown in Fig. 1.

65 Referring to the drawings and more specifically to Figures 1 and 2 which more or less

diagrammatically illustrate a double reduction gear unit which has been chosen as illustrative of the present invention. In this chosen illustration two turbines are illustrated comprising a high pressure turbine 70 1 and a low pressure turbine 2 which are mounted in suitable casings and bed plates to be set in accordance with engineering practice. Each of these turbines are provided with couplings 4 which connect the 75 turbines with the shafts 5 of the first stage reduction gear pinions 6 and 7. The reduction gear pinions 6 mesh with large gears 8 mounted on the shaft 9 and the reduction pinions 7 driven by the low pressure turbine 80 2 mesh with large gears 10 on the shaft 11. The shaft 9 carries second stage reduction pinions 12 and the shaft 11 similarly carries second stage reduction pinions 14. These reduction pinions 12 and 14 mesh with 85 the main gears 15 which are securely mounted upon the main shaft 16 that is adapted to be connected to the propeller shaft (not shown) by means of a coupler 17. The construction described, so far as general arrangement and organization is concerned, is 90 common practice.

The present invention comprises more specially the arrangement of the teeth, shafts, bearings and couplings in reversed 95 symmetry. Preferably the teeth are arranged in such manner that a central plane cutting a gear at right angles to its axis will divide the gear in such manner that when either side is reversed and placed in position of the adjoining side, the angle and shape of the teeth on the replaced side will be exactly the same as the angle and shape of the teeth of the original side of the gear. Preferably this arrangement is carried out 100 through the entire set of gears so that the shape and size of the gear teeth on the gearing lying on one side of the central plane cutting the axes of the set or unit will be congruous to the shape and size of the 110 gear teeth on the other side of the plane. This may be carried out by providing the gears with teeth arranged as shown in Figure 1 wherein each main gear 15 is divided on its tooth face to comprise teeth 18 inclined clockwise on one spiral, and teeth 19 inclined counter-clockwise on the opposite spiral. The same arrangement is carried out as to the pinions 12 and 14 and also as to the large gears 8 and 9.

Reference will now be made to Figures 3 and 4 wherein the gear teeth are shown diagrammatically and the teeth on one half of the gear set are shown in full lines while the teeth on the other half of the gear set 125 are shown in dotted lines, in order to distinguish the teeth so that they may be followed by explanation when the reversal has been made. The set of teeth A are shown in full lines and the set of teeth B are shown 130

in dotted lines. In Figure 4 the shaft 9 has been reversed, that is, it has been turned end for end, so that the pinion B^{12} is now in engagement with the teeth of the large gear

5 A^{15} and the pinion A^{12} is in engagement with the teeth of the large gear B^8 . The effect of this reversal of the shaft 9 is shown also in Figures 5 and 6. In Figure 5, which is a diagrammatic end view of Figure 3, the stern faces on the several gears are shown in shaded lines. By stern faces is meant the side of the faces of the teeth which carry the load when the steamer is going astern and consequently the shaded portions of the

15 teeth represent those parts which receive the least wear in the normal operation of the gear unit.

Referring to Figure 5 that illustrates an end view of Figure 3 looking in the direction 20 of the arrow X, and which shows the arrangement before reversal, it will be noted that the pinion B^{12} is in engagement with the main gear B^{15} and that the first reduction gear B^6 is in engagement with the large 25 reduction gear B^8 . Referring now to Figure 6, which represents the end view of Figure 4 looking in the direction of the arrow Y, and which shows the parts after reversal, it will be noted the second reduction gear A^{12} is now in engagement with main gear B^{15} and the first gear A^6 is in engagement with the large gear A^8 . It will now be noted that the shaded portions of the teeth which were the stern sides of the 35 teeth have now become the driving side or forward side of the teeth on the gears, excepting the main gear B^{15} which is so large that the wear thereon is very small, and it need not be reversed until several pinions 40 have been worn out.

It is to be understood that where a connection is required on the end of a shaft which is to be reversed a construction must be provided on both ends of the shaft in 45 order to permit a connection to be made, as for example the taper and key way 20 on the ends of the shafts 5 so that proper connection can be made with the couplers 4 when the shafts 5 are reversed.

50 Referring now to Figure 7 which illustrates a construction permitting the reversal of the main gears without reversing the main shaft 16, the gear frame C^{15} is provided with seat faces 21 and 22 which are slightly tapered and on which main gear teeth rings 24 and 25 are adapted to be held by means of 55 stub screws 26 that are screw threaded into the body C^{15} and extend through the flanges 27 and 28 on the rings 24 and 25. These 60 stub screws clamp the gear teeth rings very tightly upon the gear wheel frame so that the gear teeth rings are very rigidly held in place. Suitable keys one of which is shown at 30 are adapted to interlock each of the 65 gear teeth rings and the body so that the

parts are very securely united. By this construction it will be evident that the gear ring 24 may be interchanged in position for the gear ring 25, thus effecting a reversal of the teeth.

70

From the foregoing it will be clear that the present construction provides great economy in the use and treatment of large gears which, because of the enormous horse power transmitted, are necessarily helical gears. 75 By this arrangement it will appear that the life of a gear set is greatly increased.

The present invention is particularly useful in overcoming vibration due to wear in the gearing. The operators of steam turbine 80 plants locate difficulties by sound and when the gears wear so that vibration becomes excessive the effect on the morale of the operators is very depressing because it destroys the element on which they depend for safety, 85 by finding trouble before it becomes disastrous. Furthermore this invention provides for the renewed relation being accomplished by merely reversing symmetrical interfitted parts, so that the renewal may be made at 90 sea or elsewhere with no special machinery required other than that needed to handle the heavy parts.

Having thus described our invention, what 95 we claim is:

1. Driving mechanism for steamships comprising a large driven gear having teeth in reversed symmetry about a plane perpendicular to the mid point of its axis and constructed to permit ready reversal to change 100 the trailing faces of the teeth to forward faces; an intermediate shaft symmetrical about its mid point; intermediate gear means mounted centrally on said intermediate shaft, the teeth of said intermediate gear means being in reversed symmetry about a plane perpendicular to the mid point of the intermediate shaft to permit the intermediate gear to be reversed by reversing the intermediate shaft in its bearings; a pinion 105 shaft symmetrical about a plane perpendicular to its mid point; and a pinion mounted centrally on said shaft, said pinion having its teeth in reversed symmetry about a plane perpendicular to the mid point of the shaft to permit the pinion to be reversed by reversing the pinion shaft in its bearing; said construction permitting the ready reversal 110 of all gear elements of the series whereby when teeth become worn all of the gear elements may be reversed to change all of the trailing faces into forward faces.

115 2. A power plant for steamships comprising a large gear adapted to be connected with a propeller shaft; a pair of intermediate shafts, each of said shafts being symmetrical about a plane perpendicular to the mid point of the shaft; intermediate gear means mounted centrally on said intermediate 120 shafts and operative to transmit power 125 130

to the large gear, each of said intermediate gear means having teeth in reversed symmetry about a plane perpendicular to the mid point of its shaft whereby when the 5 intermediate gear teeth become worn the intermediate shafts may be readily reversed in their bearings to cause the trailing faces of the intermediate gear teeth to become forward faces; a pair of pinion shafts, each 10 symmetrical about a plane perpendicular to its mid point and having both ends formed for attachment to the same coupler; a pair of steam turbines, one coupled to each of

said pinion shafts, and pinions mounted centrally of the pinion shafts, each of the pinions having teeth in reversed symmetry about a plane perpendicular to the mid point of the pinion shaft whereby when the pinion teeth become worn, the pinion shafts may be readily uncoupled from the turbines 15 and reversed in their bearings to cause the trailing faces of the pinion teeth to become forward faces.
